HOPPER

Joseph S. Bennett, Merion, Pa., assignor to American Engineering Company, Philadelphia, Pa., a corporation of Pennsylvania

Application September 28, 1932, Serial No. 635,190

4 Claims. (Cl. 110—167)

This invention relates to hoppers, and more particularly to hoppers employed in boiler furnaces having in conjunction therewith troughs into which the water for quenching the ash may drain. In hoppers of this character it frequently happens that considerable refuse enters the trough from the hopper with the water, causing the outlet discharge of the trough to clog. When this occurs the water flows over the walls of the trough and spills onto the floor therebeneath. In order to receive the water draining from the hopper and to conserve space, the trough must necessarily be positioned in close proximity to the hopper and because of this it is difficult to remove the refuse collected therein.

The primary object of the present invention, therefore, is to provide means whereby the trough may be dumped at intervals so that any foreign matter collected therein will be discharged therefrom.

A more specific object of the present invention is to provide novel mechanism for dumping the trough, which functions independently of operating mechanisms for the hopper gates.

Other and further objects will become apparent as the description of the invention progresses.

Of the drawings:

Fig. 1 is an end view of a hopper showing the position of the trough with respect thereto and the operating mechanism for said trough.

Fig. 2 is a side elevational view of the hopper and trough shown in Fig. 1.

Fig. 3 is a sectional view taken substantially on line 3—3 of Fig. 2, and

Fig. 4 is an end view of a modified trough construction and operating mechanism therefor.

The hopper 1 shown herein is of the general type disclosed in United States application Serial No. 282,776, filed June 4, 1928, and comprises side walls 2 and 3, and end walls 4 and 5. Hopper 1 may be secured to the walls of an ash pit so that the ashes discharging from the furnace may enter the same by gravity. The bottom opening of the hopper is normally closed by a pair of swinging gates 6 and 7, the side supporting members 8 and 9 of which are pivotally supported upon pins 10 and 11 secured to brackets 12 and 13 provided on the end walls 4 and 5 respectively. The side supporting members 8 and 9 are provided with intermeshing segmental gear members 14 and 15. The lower edge of each gate 6 is provided with a tooth section 16 which meshes with a gear 17 secured to a shaft 18 extending lengthwise of the hopper. Shaft 18 is suitably journaled in brackets 19 secured to and extending outwardly from

end walls 4 and 5. The supporting members 8 and 9 for the gates 6 and 7 are respectively provided with enlarged openings 20 and 21, thus permitting swinging movement of the gates. From the construction of the elements just described, it is seen that upon actuation of shaft 18, gears 17 will simultaneously swing the gate members 6 and 7 in opposite directions about pins 10 and 11.

A bridge member 22 secured to end walls 4 and 5 near the lower edges thereof, substantially midway between side walls 2 and 3, is provided to deflect the ash from a trough 24 supported therebeneath when the gates 6 and 7 are opened. As shown in Fig. 3, the inner edges of gates 6 and 7 are spaced apart forming a drain for the hopper. As stated, the bridge 22 is provided to deflect the ash from trough 24 and thus prevent damage thereto. It is apparent, however, that the trough may be constructed sufficiently rugged as not to be damaged by falling ash, and in such constructions the bridge 22 may be eliminated. Trough 24 has secured to the ends thereof pins 25 and 26, respectively, which extend through apertures provided in brackets 27 and 28, secured, respectively, to end walls 4 and 5. Secured to pin 25 is a gear 29 which meshes with a segmental gear 31 rotatably mounted upon a pin 32 secured to bracket 27. The outer end of an arm 33 integral with segmental gear 31 is pivotally attached to one end of a link 34. The other end of said link is pivotally attached to the upper end of an arm 35 rotatably mounted upon a pin 36 secured to end wall 4, as shown in Fig. 1. Depending from pin 36 and secured to arm 35 is a hand operated lever 37. A plate 38 is also secured to end wall 4 and is provided with two or more radial slots 39 and 40 respectively. A hand operated detent 41 is slidably mounted in suitable guides 42 provided on lever 37 and a spring 43 normally urges said detent 41 into slot 39 provided in plate 38. A link 44 is pivotally attached to detent 41 and lever 37 near the lower ends thereof. It therefore is seen that by drawing the lower end of detent 41 toward lever 37 link 44 will be rocked downwardly, thus causing detent 41 to move out of engagement with slot 39.

From the construction of the elements just described, it is seen that in order to tilt trough 24, the operator simply grasps the lower end of lever 37 and detent 41, whereby detent 41 will immediately be released from locking engagement with plate 38, and then swings said lever in a counter-clockwise direction. This movement is immediately imparted to trough 24 through link 34, and gears 31 and 30, causing said trough to swing about its pivot. When the lever 37 has been

swung so that detent 41 registers with slot 40 in plate 38, trough 24 will have been swung through an angle of substantially 180 degrees, and any foreign matter collected therein will be discharged. By releasing the grip on detent 41 spring 43 will urge said detent into locking engagement with plate 38 and the trough will thus remain in operated position. Trough 24 is provided with a discharge opening 45 which communicates with a spout 46, secured to a bracket 47 which is supported upon a pin 26. Spout 46 communicates with a drain pipe 48 which in turn communicates with the main drain of the plant.

In Fig. 4, I have shown a modified form of trough mechanism. In this construction a trough 50 is pivotally supported in brackets 51 secured to gate 6 of the hopper. An arm 52 integral with trough 50 has pivotally attached to the outer end thereof a link 53, the upper end of which is pivotally secured to a block 54. Block 54 is adjustable between guides 55, secured to end wall 4 of the hopper, so that when the apparatus is assembled, block 54 may be adjusted to properly position trough 50. Block 54 is then secured in this position by any suitable means.

The operation of this construction is thought to be obvious. When gates 6 and 7 are swung to open position the trough 50 is carried by gate 6 and automatically tilted by virtue of the link connection 53. The trough is thus swung out of the path of the ash gravitating from the hopper and at the same time is tilted so that any refuse collected therein is discharged. In this construction the provision of a bridge in the hopper is unnecessary.

For the purpose of illustration the trough constructions herein described are shown as employed with hoppers having a pair of swinging gates. It is obvious, however, that they are equally applicable to hoppers wherein a pair of sliding gates are employed to close the discharge opening, or to hoppers wherein a single swinging or sliding gate is employed. It therefore is to be understood that it is not intended to confine the invention to the embodiments herein shown since it may be embodied in other forms all coming within the scope of the claims which follow.

What is claimed is:

1. A hopper, having side and end walls termi-

nating in a discharge opening, closure means normally closing said opening, said closure means having a drain provided therein, a trough disposed beneath said drain and pivotally supported on said closure means, and linkage pivotally connecting said trough to one of the walls of said hopper, whereby movement of said closure means to open position causes tilting of said trough, and movement of said closure means toward closed position restores said trough to normal position. 10

2. A hopper having side and end walls terminating in a discharge opening, closure means normally closing said opening, said closure means having a drain provided therein, a trough disposed beneath said drain, means for pivotally supporting said trough on said closure means, and means connecting said trough to a fixed support whereby movement of said closure means toward open position causes tilting of said trough to discharge any material collected therein, and movement of said closure means toward closed position restores said trough to normal position, and means for moving said closure means to open and closed position. 20

3. A hopper having a discharge opening, a pair of gates normally closing said opening, said gates having a drain disposed along the abutting edges thereof, a trough disposed beneath said drain and pivotally supported upon one of said gates, means connecting said trough to a fixed support, whereby movement of said gates to open position causes tilting of said trough to discharge any material collected therein, and movement of said gates toward closed position restores said trough to normal position, and means for operating said gates to open and closed position. 30

4. A hopper having a discharge opening, closure means normally closing said opening, said closure means having a drain provided therein, a trough disposed beneath said drain and pivotally supported on said closure means, an arm secured to and extending outwardly of said trough, and a link connecting said arm to a fixed support, whereby movement of said closure means to open position causes tilting of said trough to discharge any material collected therein, and movement of said closure means toward closed position restores said trough to normal position. 40

JOSEPH S. BENNETT.
